UNITED STATES PATENT OFFICE.

ALBEN E. LUNDELL, OF CHICAGO, ILLINOIS, ASSIGNOR TO WESTERN ELECTRIC COMPANY, INCORPORATED, OF NEW YORK, A CORPORATION OF NEW YORK.

TELEPHONE-EXCHANGE SYSTEM.

1,410,766.

Specification of Letters Patent. Patented Mar. 28, 1922.

Application filed October 16, 1919. Serial No. 331,057.

To all whom it may concern:

Be it known that I, ALBEN E. LUNDELL, a citizen of the United States, residing at Chicago, in the county of Cook, State of Illinois, 5 have invented certain new and useful Improvements in Telephone-Exchange Systems, of which the following is a full, clear, concise, and exact description.

This invention relates to improvements in 10 telephone exchange systems, and particularly to a circuit arrangement for controlling the operation of the selector switches.

An object of the invention is to increase 15 the speed of selection by the automatic switches without sacrificing accuracy and also to reduce the amount of controlling equipment for measuring off the travel of the switches. Heretofore, as shown for example in the patent to Lundell No. 1,168,319, 20 impulses were transmitted to the counting relays due to the shunting of the stepping relay by a commutator brush passing over the commutator plate, which plate had a segment for each line terminating in the switch. 25 These relays measured off the travel of the selector and when a predetermined segment was reached, the corresponding relay operated to stop the switch at which time the talking brushes were in contact with the de- 30 sired line.

In carrying out this invention, instead of providing a commutator segment for each line terminating in the switch, one segment is provided for every other line in one commutator plate and an additional commutator plate adjacent the first plate carries segments for the lines not represented on the first plate 35 and an extra contact is provided on the key set which is closed if the digit of the called 40 number is of a certain character, for example, odd. As the commutator brush is traveling over the first named plate an impulse is transmitted to the stepping relay of the sender for each segment encountered, this 45 stepping relay operating the counting relays in succession, and when the last counting relay pair is reached and the fundamental circuit opened, the selector stops if the digit is, for example, even, but if odd, a circuit 50 prepared by the said extra contact is closed, including the second commutator plate. This circuit provides a substitute path to hold the selector power magnet energized until the

selector reaches the next set of talking terminals.

The same arrangement may be applied to group selection; that is, if the tens digit of the called number is odd, the selector is stopped when the last counting relay pair operates, but if the said digit is even, a substitute circuit is closed, including the extra group commutator plate, and an extra contact of the tens keys to maintain power applied to the selector until it reaches the beginning of the subsequent group.

Referring to the drawings, Figs. 1 and 2 illustrate diagrammatically a circuit arrangement for carrying out the invention applied to a semi-automatic telephone system.

The selector switches employed in this system may be of the type disclosed in the patent to Craft and Reynolds No. 1,123,696, and a complete operating circuit for these switches is disclosed in said Patent No. 1,168,319. The registering and controlling 70 devices of the above mentioned patent to Lundell may also be employed in this system. In this invention sequence switches are employed that are similar in construction to that disclosed in the patent to Reynolds and Baldwin No. 1,127,808, and they are similar 75 in operation and function to that disclosed in the patent to McBerty No. 1,125,579.

Since the general operation and arrangement, as disclosed in the above mentioned 80 patents, does not form a part of this invention, the greater part of it has been omitted and only sufficient portions thereof have been disclosed to set forth their relation to this 85 invention.

It is to be understood that, although only a single selector switch has been shown and described in this application, in actual practice a series of such selectors may be employed. The switch shown in this system 90 would be classed as a final selector in such an arrangement, but in order to bring out the invention more clearly it has been shown connected directly with the operator's cord circuit in the same manner in which a district switch would have been connected. It is believed that by describing the various operations necessary for setting up a connection between the calling subscriber's station indicated at A and the called subscriber's station indicated at B, the invention 95

will be readily understood. However, only the operations most intimately related to the invention will be described, and as to the remaining operations, reference may be had 5 to the above mentioned patents.

When the subscriber at A removes his receiver from the switchhook, a circuit is completed from battery through the left-hand winding of line relay 110, back contact and 10 outer left-hand armature of cutoff relay 111, the subscriber's apparatus at A, the back contact and inner left-hand armature of relay 111, and right-hand winding of line relay 110, to ground. Line relay 110 attracts its armature and thereby completes 15 a local circuit for lighting the lamp 113. The operator observing that the lamp is lighted, inserts the answering plug 114 of a cord circuit 115 in the answering jack of 20 the calling line. The cutoff relay 111 and relay 117 are thereupon energized in series over a circuit extending from battery, winding of cutoff relay 111, sleeve of jack 116, sleeve of plug 114 and winding of relay 117, 25 to ground. These relays attract their armatures and the cutoff relay 111 interrupts the energizing circuit of the line relay 110 which on the retraction of its armature interrupts the circuit of the lamp 113. The 30 relay 117 on attracting its armature completes a circuit from battery, power magnet of sequence switch 100, upper left-hand sequence switch contact 118, front contact and armature of relay 117, to ground, to 35 move the sequence switch 100 out of position 1 into position 2, under the control of its master contact 120. In position 2 of sequence switch 100, a circuit is completed from battery, relay 210, upper sequence 40 switch contact 211, conductor 212, lower sequence switch contact 122 to ground. Relay 210 is energized and completes a locking circuit for itself from battery, the lower sequence switch contact 211, armature and 45 front contact of relay 210, conductor 215, upper sequence switch contact 122, to ground. The operation of relay 210 completes a circuit for sequence switch 200 from 50 battery, sequence switch magnet 200, upper right-hand sequence switch contact 216, front contact and left-hand armature of relay 210, to ground, to move the sequence switch 200 out of position 1 into position 3, under the control of its master contact 55 219.

While these operations are taking place, the operator is connected with the calling subscriber through a listening key in an associated circuit arrangement, not shown, 60 and she ascertains thereby the number of the desired line. It will be assumed that the number wanted by the calling subscriber is 29. The operator thereupon depresses the keys 2 and 9, shown on the 65 rows of keys C and D respectively. In de-

pressing key No. 2 or any even numbered key in row C, contact 247 remains open. If an odd numbered key is depressed, contact 247 closes. Contact 243 is controlled in the same manner by the depression of the odd 70 numbered keys in set D.

After depressing the keys No. 2 of the tens group C and No. 9 of the units group D, the operator depresses the starting key 225 which closes a circuit for moving the 75 sequence switch 200 out of position 3 and into position 4. This circuit may be traced from battery, sequence switch 200, lower sequence switch contact 216, starting key 225, to ground. 80

With the sequence switch 200 in position 4 and sequence switch 100 in position 2, a fundamental circuit is established from battery, relay 125, lower sequence switch contact 128, conductor 129, contact 228, stepping relay 229, the sequence switch contact 230, conductor 231, sequence switch contact 130, to ground. Relay 125 is energized and establishes a locking circuit for itself by way of its left-hand armature and front 90 contact and over the circuit just traced. The operation of relay 125 completes a circuit from battery, sequence switch magnet 100, conductor 134, upper sequence switch contact 135, front contact and right hand 95 armature of relay 125, to ground, for moving the sequence switch 100 out of position 2 and into position 3. In position 3 of sequence switch 100 a circuit is completed from battery, up-drive power magnet 139, 100 lower right-hand sequence switch contact 135, front contact and right-hand armature of relay 125, to ground. This circuit energizes the up-drive power magnet which elevates a brush shaft 140 of the switch E. As 105 the brush shaft is elevated, the brushes 141, 142, 143 and 144 are brought into engagement with their respective commutators 145, 146, 147 and 148, and as the brush 141 passes over the conducting segments of the 110 commutator 145, a circuit is completed from battery, relay 125, conductor 129, upper right-hand sequence switch contact 128, conductor 150, commutator 145, and brush 141, to ground. As the switch is advanced this 115 circuit acts as a short circuit for the stepping relay 229, which is thereby permitted to alternately energize and deenergize.

When the stepping relay was originally energized, a circuit was completed from battery, counting relay 233, armature and back contact of counting relay 234, key No. 2 in the tens group, left-hand sequence switch contact 235, conductor 236, armature and front contact of stepping relay 229, to 120 ground. This circuit energized relay 233 which completed a locking circuit for itself and a circuit for relay 234 from battery, windings of relays 233 and 234, armature and front contact of relay 233, right-hand 125 130

sequence switch contact 237, to ground. This circuit does not become effective to energize relay 234 until after the stepping relay 229 has been deenergized because relay 234 is shunted by the ground at its back contact. When stepping relay 229 deenergizes it removes the ground from the conductor 236, when said circuit energizes relay 234 and locks up the two relays 233 and 234 in series. The stepping relay 229 is again energized when the brush 141 passes off the first conducting segment of commutator 145 and a circuit is now completed from relay 238 by way of the armature and front contact of relay 234 to the key No. 2 in group C. As soon as the brush 141 comes in contact with the second conducting segment of commutator 145, stepping relay 229 is again deenergized. This time the deenergization of stepping relay 229 causes the relay 239 to be energized and relays 238 and 239 to be locked up in the same manner as were relays 233 and 234. The energization of relay 239 opens the fundamental circuit at contact 228 and the relay 125 will therefore be permitted to deenergize as soon as brush 141 has passed off the second conducting segment of commutator 145 which controls the switch actuation from 20 to 39, the first conducting segment controlling said actuation from 0 to 19. In deenergizing, relay 125 breaks at its right-hand armature and front contact, the circuit previously maintained for power magnet 139, thus bringing the switch brushes to rest.

The operation of relay 239 also completes a circuit from battery, sequence switch 200, outer armature and front contact of relay 239, left-hand sequence switch contact 237, to ground, for moving the sequence switch 200 out of position 4 into position 6. The counting relays are thereby unlocked and deenergized and the fundamental circuit is again closed at contact 228. The deenergization of relay 125 completed a circuit from battery, sequence switch 100, sequence switch contact 152, outer left-hand armature and back contact of relay 153, right-hand armature and back contact of relay 125, to ground, to move sequence switch 100 out of position 3 into position 6.

With sequence switch 200 in position 6 and sequence switch 100 in position 6, the fundamental circuit is again established; relay 125 is energized and locked up through the same circuit as before, and a circuit completed from battery, sequence switch 100, conductor 134, upper sequence switch contact 135, right-hand armature and front contact of relay 125, to ground, to move sequence switch 100 into position 7.

As the unit key selected in this case was assumed to be an odd number (9), the selector operates in a manner different from that described as taking place when an even

number was selected. The stepping relay 229 is alternately deenergized and energized in the same manner as before but the deenergization is taking place over a different shunt circuit which may be traced from battery, left-hand armature and front contact of relay 125, conductor 129, left-hand sequence switch contact 128, conductor 154, commutator 147, brush 143, to ground. The counting relays are locked up in succession beginning with the fifth set as the brush 143 passes over the conducting segments of the commutator 147. When the fifth conducting segment in the third group on commutator 147 is passed by the brush 143, the last set of counting relays 238 and 239 are locked up and the fundamental circuit is broken. Relay 125 is deenergized as before. The brushes 164, 165, 172 on the brush shaft 140 have by this time reached the ninth terminal in the bank F. Due to the fact that the contact 243 is closed in the case assumed, the energizing circuit for the power magnet 139 is not broken at this time but maintained until the brushes reach the tenth terminal corresponding to the No. 9 unit key. Power magnet 139 is maintained energized over a circuit from battery, power magnet 139, lower sequence switch contacts 135, front contact and inner left-hand armature of relay 153, to ground. The relay 153 is energized at this time by a circuit from battery, relay 153, conductor 242, contact 243, right-hand sequence switch contact 245, conductor 246, left-hand sequence switch contact 158, commutator 148 and brush 144, to ground.

The relation of the conducting segments on the commutator 148 to the conducting segments on the commutator 147 is such as to complete this energizing circuit for relay 153 before relay 125 is permitted to deenergize, thus maintaining the circuit for moving the sequence switch 100 out of position 7 open at the outer left-hand armature and back contact of relay 153. This circuit for sequence switch 100 would ordinarily be completed at the right-hand armature and back contact of relay 125 as soon as it is deenergized. In this case, however, the relay 153 is maintained energized over a locking circuit from battery, winding, right-hand armature and front contact of relay 153, sequence switch contact 159, left sequence switch contact 158, commutator 148, and brush 144, to ground. The position of the conducting segments on commutator 148 in relation to brush 144 is such as to maintain this locking circuit and keep the switch moving until its brushes reach the tenth set of terminals on the bank F. When the brushes are accurately located on the terminals, this locking circuit is broken and relay 153 permitted to deenergize. The switch is then stopped by the breaking of the

branch of the energizing circuit for the power magnet 139 maintained through the inner left-hand armature and front contact of relay 153.

- 5 When relay 239 was energized a circuit was completed from battery, sequence switch 200, outer armature and front contact of relay 239, left-hand contact of sequence switch contact 237, to ground, for moving sequence switch 200 from position 6 into position 16. When relay 153 deenergizes, a circuit is completed from battery, sequence switch 100, sequence switch contact 152, outer left-hand armature and back contact of relay 153, right-hand armature and back contact of relay 125, to ground, for moving the sequence switch 100 out of position 7 into position 11. With the sequence switch 200 in position 16 and the sequence switch 100 in position 11, the locking circuit for relay 210 is broken at lower sequence switch contact 211. The deenergization of relay 210 completes a circuit from battery, sequence switch power magnet 200, left-hand sequence switch contact 216, left-hand armature and back contact of relay 210, to ground, for moving sequence switch 200 out of position 16 into position 18. In position 18 of sequence switch 200, a circuit is completed from battery, sequence switch 100, lower sequence switch contact 118, conductor 248, sequence switch contact 249, to ground, for moving the sequence switch 100 out of position 11 into position 16. In position 16 of sequence switch 100, the talking conductors 160 and 161 are extended through sequence switch contacts 162 and 163, brushes 164 and 165, terminals 166 and 167 and line conductors 168 and 169 leading to the called subscriber's station at B. In position 16 of sequence switch 100, a busy test ground through resistance 170 and sequence switch contact 171 is placed on the test brush 172 and terminal 173 to protect the line from being seized by another selector switch.

At the close of the conversation, the supervisory relays 174 and 175 operate in the well known manner to indicate the termination 50 of the call to the operator. The operator then removes the plug 114 from jack 116 and causes the relay 117 to be deenergized. At the retraction of the armature of relay 117, a circuit is completed from battery, sequence switch 100, upper right-hand sequence switch contact 118, armature and back contact of relay 117, to ground, to move the sequence switch 100 out of position 16 into position 18. In position 18 of sequence 60 switch 100, a circuit is completed from battery, down-drive power magnet 176, sequence switch contact 178, to ground, to drive the selector back to normal position. When the selector has been restored to normal, a circuit is completed from battery, sequence

switch 100, conductor 134, sequence switch contact 179, commutator segment 180, brush 141, to ground, to move the sequence switch 100 from position 18 back to normal position. The sequence switch 200 and key sets 70 C and D are restored to normal position in the well known manner shown in the above mentioned patents.

Let it be assumed that the tens digit was 3 instead of 2. In this case, the contact 75 247 would be closed. Two sets of counting relays would be locked up and in response to the two deenergizations of the stepping relay 229, the brushes 141, 142, 143, 144 would be stepped to the beginning of the 80 third group. In this position brush 142 would engage the second conducting segment of the commutator 146 and, contact 247 being closed, the up-drive magnet 139 would continue to operate to move the 85 brushes over the third group and to the beginning of the fourth group. At this time brush 142 will pass from said second conducting segment of commutator 146 and the brushes will come to rest.

That this arrangement is advantageous is readily seen, as the equipment of counting relay pairs is only half of what is ordinarily required and the speed of the selector switches may be considerably increased 95 without impairing accuracy of selection, due to the fact that a selector can advance a distance equal to the two groups of individual line contacts for every operation of a counting relay pair.

What is claimed is:

1. In a telephone system, incoming lines, outgoing line contacts, a switch for associating said incoming lines with any one of said contacts, a controlling device for directing the switch to an alternate contact, and means to direct the switch to an intermediate contact that lies beyond the last alternate contact reached at the termination of any particular selecting movement of the 100 switch.

2. In a telephone system, incoming lines, outgoing line contacts, a switch for associating said incoming lines with any one of said contacts, a commutator segment representing every alternate contact, means cooperating with said commutator segment to direct the switch to a predetermined one of said alternate contacts, a second commutator segment representing every other contact, 115 and means cooperating with said second commutator segment to continue to direct the switch to a contact located beyond the alternate contact to which the switch was primarily directed.

3. In a telephone system, incoming lines, outgoing line contacts, a switch for associating said incoming lines with any one of said contacts, a commutator segment representing every alternate contact, a switch 120

90

100

105

110

115

120

125

130

operating means, means cooperating with said commutator segment to control said switch operating means to connect the switch to a predetermined one of said alternate contacts, a second commutator segment representing every intermediate contact, and means cooperating with said second commutator segment to continue to control said switch operating means to connect the switch 10 to the intermediate contact located beyond the last alternate contact selected.

4. In a telephone system, incoming lines, alternate and intermediate line contacts, a switch for associating said incoming lines with any one of said contacts, means to direct the switch to any one of the alternate contacts, means to direct the switch to the last alternate contact in any particular selecting movement, and means to continue to 20 direct the switch to the next intermediate contact at the termination of said particular selecting movement.

5. In a telephone system, incoming lines, outgoing line contacts, a switch for associating said incoming lines with any one of said contacts, a commutator having segments representing every alternate contact, selectively operable counting relay sets representing every alternate contact, means 30 operating with said commutator segments and counting relays to direct the switch to the alternate contact corresponding to the selected counting relay set, and means to continue to direct the switch to another contact adjacent the alternate contact selected.

6. In a telephone system, incoming lines, outgoing line contacts, a switch for associating said incoming lines with any one of said contacts, a commutator having segments representing every alternate contact, counting relay sets representing every alternate contact, selecting means for said counting relay sets, means cooperating with said commutator and said counting relays to direct the switch to the alternate contact corresponding to the selected counting relay set, and means to continue to direct the switch to another contact adjacent the alternate contact selected.

50 7. In a telephone system, incoming lines, outgoing line contacts, a switch for associating said incoming lines with any one of said contacts, a commutator having segments for every alternate contact, counting relay sets 55 for said alternate contacts, selecting means for said counting relay sets so arranged as to select the same set of counting relays for a corresponding alternate contact and the succeeding intermediate contact, means operating with said commutator and said counting relays to direct the switch to the alternate contact corresponding to the selected counting relay set, and means to continue to direct the switch to the intermediate contact 65 succeeding the alternate contact selected.

8. In a telephone system, incoming lines, alternate and intermediate line contacts, a switch for associating said incoming lines with any one of said contacts, means to direct the switch to the last alternate contact in any particular selecting movement, means to continue to direct the switch to the succeeding intermediate contact at the termination of said selecting movement, and a selecting means for said directive means. 75

9. In a telephone system, incoming lines, alternate and intermediate line contacts, a switch for associating said incoming lines with any one of said contacts, means to direct the switch to a predetermined alternate contact in any particular selecting movement, means to continue to direct the switch to the succeeding intermediate contact, and a selecting means common to said directive means for jointly controlling the same. 80 85

10. In a telephone exchange system, a switch, sets of line terminals therein, a plate thereon having a contact for every other set of terminals, a number of pairs of counting relays equal to the number of contacts on said plate, a key set having a contact closed when the digit key operated corresponds to a line terminal set not represented on said plate, a circuit for operating said relays in succession to measure off the travel of the switch, and a circuit including said key set contact for continuing the travel of the switch to the next set of line terminals after the last counting relay pair has operated. 90 95

11. In a telephone exchange system, a switch, sets of line terminals therein divided into groups, a commutator plate carried by said switch having a contact for every other group of line terminals, a number of pairs of counting relays equal to the number of contacts on said plate, a key set having a contact closed when the digit key operated corresponds to a line set not represented on said plate, a circuit for operating said relays in succession to measure off the travel of the switch, and a circuit including said key set contact for continuing the travel of the switch to the next group of line contacts after the last counting relay pair has operated. 100 105 110 115

12. In a telephone exchange system, a switch, sets of line contacts thereon, a commutator plate having a segment for every other set of terminals, pairs of counting relays equal in number to the number of segments, a key set having a contact closed when the digit key operated corresponds to a terminal set not represented on the commutator, a fundamental circuit for maintaining power applied to the switch, said relays controlling said circuit and opening the same when the last of said relays operates, a second commutator plate, and a circuit including the same and said contact when closed to maintain power applied to the 120 125 130

- switch to continue its travel to the next line terminal set. the termination of any particular selecting movement of the switch.
13. In a telephone system, telephone lines, a switch for interconnecting said lines, a key set for controlling said switch, an extra contact on said key set responsive in its actuation to the actuation of alternate keys in said set, and means responsive to the actuation of said extra contact for causing said switch to move an additional step. 15. In a telephone system, incoming lines, outgoing line contacts, a switch for associating said incoming lines with any one of said contacts, a controlling device for directing the switch to one of said contacts and means to direct the switch to another contact that lies beyond the contact reached at
- 10 14. In a telephone system, incoming lines, outgoing line contacts, a switch for associating said incoming lines with any one of said contacts, a controlling device for directing the switch to a predetermined contact and means to direct a switch to another contact beyond the predetermined contact reached at the termination of the movement of the switch which selected the said predetermined contact. 20 25
- In witness whereof, I hereunto subscribe my name this 9th day of October, A. D., 1919.

ALBEN E. LUNDELL.
